CLAIM

I claim the ornamental design for a wireway, as shown and described.

DESCRIPTION

FIG. 1 is a perspective view of the wireway in accordance with my new design;

FIG. 2 is a side elevational view thereof;

FIG. 3 is a front elevational view thereof;

FIG. 4 is a top plan view thereof;

FIG. 5 is a bottom plan view thereof;

FIG. 6 is a rear elevational view thereof; and,

FIG. 7 is an opposite side elevational view thereof.

The broken lines showing of bolts is for illustrative purposes only and forms no part of the claimed design.
